US00D925585S

(12) **United States Design Patent** (10) **Patent No.:** **US D925,585 S**
(45) **Date of Patent:** **** Jul. 20, 2021**

(54) **DISPLAY SCREEN OR PORTION THEREOF
WITH GRAPHICAL USER INTERFACE**

(71) Applicant: **Caterpillar Inc.**, Peoria, IL (US)

(72) Inventors: **Keith Folken**, West Peoria, IL (US);
Mitchell B. Howard, Lebanon, IN (US); **Mukund Jaganmohan**, Chennai (IN); **David Ochoa**, Boynton Beach, FL (US); **Bhaskara Rao Polisetty**, Nellore (IN)

(73) Assignee: **Caterpillar Inc.**, Peoria, IL (US)

(**) Term: **15 Years**

(21) Appl. No.: **29/759,396**

(22) Filed: **Nov. 23, 2020**

Related U.S. Application Data

(63) Continuation of application No. 29/714,839, filed on Nov. 26, 2019, now Pat. No. Des. 910,693, which is a continuation of application No. 29/659,224, filed on Aug. 7, 2018, now Pat. No. Des. 872,109.

CLAIM

The ornamental design for a display screen or portion thereof with graphical user interface, as shown and described.

DESCRIPTION

FIG. 1 shows a display screen or portion thereof with graphical user interface showing our new design; and, FIG. 2 shows another embodiment thereof.

The peripheral dashed broken lines illustrate a display screen or portion thereof, and form no part of the claimed design.

The text illustrated in broken lines forms no part of the claimed design.
